(57) **CLAIM**

The ornamental design for an edge-emitting light emitting diode component, as shown and described.

DESCRIPTION

FIG. 1 is a front view of an edge-emitting light emitting diode component, in accordance with the new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,
